ANIMATED TOY

Nathan G. Cohen, Brooklyn, N. Y.

Application April 18, 1945, Serial No. 589,021

9 Claims. (Cl. 46—104)

This invention relates to toys, and more particularly to those of the animated type in which the legs, head, arms or other parts of the figure of an animal or human figure are caused to move in a natural and life-like manner as the toy is propelled across the floor by being pushed or otherwise moved.

I am aware that prior to this invention, efforts have been made to lend animation to the figure of an animal or the like, by movement of the figure across the floor, but in most cases an unnatural rocking movement of the body and the rigidly-attached legs of the figure was the result, so that the effect secured was quite unlike the natural running or walking movements of the animal. In other instances, where efforts were made to secure properly synchronized movements of the legs and head of the figure, considerable operating mechanism was involved, thereby making the manufacturing cost of the toy prohibitive and the selling price of the toy quite beyond the reach of the person of moderate means.

The primary object therefore, of the present invention, is to provide a toy of this character which can be inexpensively constructed of wood, light metal, ply-wood or any other suitable pressed sheet material; which will be composed of relatively few parts capable of being stamped or cut from the sheet material in quantity and which can be rapidly assembled into the finished toy. The invention further contemplates the provision of a toy of this character which, by the simple act of pushing or pulling it across the floor or sidewalk will cause the legs, head, tail and/or other parts of the figure to move in a natural and life-like manner to simulate the normal movements of the represented figure when engaged in running or walking. If for example, the figure is that of a dog or horse, which are the most commonly used animal figures in toys, the legs and head of the figure can be synchronized as to movement so that the same will move in the manner in which these parts are normally moved during running.

These and other objects are accomplished by the invention, a more particular description of which will be hereafter set forth and pointed out in the claims appended hereto.

Reference is to be had to the accompanying drawing, forming a part hereof, in which Fig. 1 is a side elevation of an animated toy constructed in accordance with the invention; Fig. 2 is a top plan view of the same; Fig. 3 is a view somewhat similar to Fig. 1, but with one of the face plates of the body removed, and some of the parts being

shown in section, and Fig. 4 is a sectional view on the line 4—4 of Fig. 3, looking in the direction of the arrows.

The toy may be almost wholly constructed from wood, ply-wood, pressed board, or any other suitable sheet material easily fabricated into the shape of the required parts. In the form shown, the toy has assumed the shape of a small animal such as a dog, but it will be apparent that it may be made in the form of other animals or other objects. The body of the animal shown is composed of two face plates of suitable shape, indicated respectively at 1 and 2, these plates being maintained in properly spaced relationship by any suitable spacing means or inserts, such means being omitted to simplify illustration of the operating parts of the toy. The toy is provided with a pair of fore legs 3 and a pair of hind legs 4, the legs being disposed on the outside of the face plates 1 and 2 in the manner clearly disclosed in the drawing. The head is shown at 5 and the same is mounted for movement between the face plates 1 and 2 in a manner to be described. In the embodiment of the invention disclosed, the toy is adapted to be propelled by being pushed across the floor or sidewalk by a child, and for this purpose a lengthy push-rod 6 is provided, the same having one end 7 anchored between the face plates 1 and 2 of the body and serving to hold these elements in their properly spaced relation.

The hind legs 4 are secured upon a pivot pin 8 mounted for rotative or oscillatory movement in the face plates 1 and 2 and the fore legs 3 are both 35 mounted upon a pivot pin 9, also arranged for rotative or oscillatory movement in the face plates 1 and 2. The head 5 is fixed upon the pivot pin 9 so that when the fore legs are swung rearwardly the head will descend and conversely, when the 40 fore legs swing forwardly the head will be raised.

Rotatively mounted upon a pivot pin 10 extending between the face plates 1 and 2, is a driving wheel or disk 11, provided in one of its faces with a substantially oval cam groove or track 12 by 45 which the legs and head are moved or animated. One of the hind legs 4 carries an inwardly projecting pin or peg 13 which enters into the cam groove 12, and one of the fore legs 3 carries a similar pin or peg 14 entering into the groove 12 at a point substantially diametrically opposite to the point of location of the pin 13.

It will be observed that the diameter of the wheel or disk 11 is such that the wheel projects below the feet 15 and 16 of the legs of the figure, 50 so that when the toy is placed on the floor or

against any other flat surface, the periphery of the wheel or disk will contact therewith and as the toy is pushed forwardly by the child, the frictional contact of the wheel with the surface of the floor will cause the wheel to be rotated. The eccentricity or oval form of the cam groove 12 is such that when the toy is pushed forwardly and the wheel or disk 11 is thus rotated, the groove 12 will act upon the pins 13 and 14 in such a manner as to move the legs of the figure with lifelike animation. That is to say, when the fore legs 3 are swung forwardly, as in Fig. 1, the head 5 is swung upwardly, and at the same time the hind legs 4 are swung rearwardly. When the front legs 3 swing rearwardly, the head descends and at this time the hind legs 4 are swung forwardly. These movements are performed by many animals in running and thus, when the toy is moved across the floor or sidewalk, a very lifelike and realistic effect of a running animal is secured. To allow clearance for the pin 13, the face plate 1 is shaped or cut away as indicated at 17, and to allow clearance for the front pin 14, the face plate 1 is provided with an arcuate slot 18 through which the pin 14 extends to reach and enter into the cam groove 12.

The structure of the toy is such that it may readily be constructed from inexpensive sheet material, yet it can be readily made of sturdy construction and capable of withstanding considerable abuse. The construction is such that it may be applied to many types of figures, animal or human, and an interesting and realistic toy is the result.

In the form shown, the toy is not self-sustaining, which is to say, it must be supported or held in operative position by the grasp of the child's hand upon the push-rod 6. By attaching a small cart to the figure, the toy will support itself, and a pull string can then be attached to the figure and the toy can then be pulled rather than pushed. Also, while the wheel or disk is shown as being rotated by frictional contact with the floor, the wheel or disk can be driven in any other suitable way, as will be clearly understood by those skilled in this art. Therefore, while I have described one embodiment of the invention, it is obvious that the same is not to be restricted thereto, but is broad enough to cover all structures coming within the scope of the annexed claims.

What I claim is:

1. A toy of the character described comprising, a figure having a body, legs pivotally attached to the body, a rotatively mounted disk in the body, said disk having a cam groove, the legs having projections entering into said groove, and the groove being eccentrically shaped to cause the legs to be moved on their pivots in proper sequence to thereby simulate the normal leg movements of the represented figure while running.

2. A toy of the character described comprising, a figure consisting of the body of an animal, legs pivoted in the body, a disk rotatively mounted in the body and having its periphery extended below the body for contact with the floor whereby said disk is rotated when the toy is moved across the floor, a cam groove provided in the disk, the legs having projections entrant into said groove, and the groove being eccentrically shaped to

cause the legs to be pivotally moved on their respective pivots in proper sequence to thereby simulate the leg movements of the illustrated animal in walking or running.

3. A toy of the character described comprising, a figure consisting of the body of an animal or the like, said body being composed of a pair of spaced face plates, legs pivotally mounted outside of the face plates, a rotatably mounted disk located between the face plates, cam means on the disk for engaging the legs, said cam means consisting of an eccentric surface operative to swing the legs on their pivots and in proper sequence to cause the movements of the legs to simulate those of the legs of the represented animal when walking or running.

4. A toy of the character described comprising, a figure of an animal having a body, limbs movably mounted thereon, a disk rotative in the body and adapted to support the body on the surface of the floor and to be rotated by frictional contact with the floor, an eccentric groove in one face of the disk and projections from the legs entering said groove, whereby said legs are pivotally moved when the disk is rotated.

5. A toy of the character described comprising, a body portion, limbs pivotal thereon, a rotatable supporting wheel mounted in the body and projecting below the same, a cam groove in the wheel, and pins projecting from the limbs and entering said cam groove whereby said limbs are animated upon rotation of the wheel.

6. A toy of the character described comprising, a body, hind legs pivoted thereon, fore legs pivoted on the body, a head fixedly secured on the pivot for the forelegs, a rotative supporting wheel rested against the surface of the floor and rotated by frictional contact with the floor, a cam groove of substantially oval formation formed in one face of the wheel between the legs, and pins projecting from the legs and disposed in the cam groove.

7. A toy of the character described comprising, a figure having a body, movable elements extending therefrom, said elements being pivotally connected to the body, a rotatable disk in the body, said disk having a cam groove, and parts projecting from the movable elements and entering the cam groove whereby said elements are oscillated by rotation of the disk.

8. A toy of the character described in claim 7, wherein said movable elements consist of the legs and head of the figure of an animal, and wherein the disk is positioned for frictional contact with the floor to enable said disk to be rotated thereby.

9. A toy of the character described comprising a figure having a body, said body consisting of a pair of similarly shaped face plates, a disk rotatively mounted between the face plates and having its edge disposed below the same, said disk being provided with a continuous cam groove, pivot pins mounted for oscillatory movement between the face plates, a pair of legs secured on each of the pins, a head secured on one of the pins, and projections from one leg of each pair entering the cam groove at such positions therein that the pairs of legs are swung to and from one another by rotation of the disk.

NATHAN G. COHEN.
